UNITED STATES PATENT OFFICE.

THEODORE H. OPPENHEIM AND BERNARD SELHORST, OF COLDWATER, OHIO, ASSIGNEES TO THE NEW IDEA SPREADER CO., OF COLDWATER, OHIO, A CORPORATION OF OHIO.

SAFETY DEVICE.

Application filed September 14, 1927. Serial No. 219,502.

Our present invention is a safety device as clearly shown in Figs. 1 and 2. To the 55 upper end of the lever 8 is attached a rod 10 which extends across the hopper, indicated at 11, and is connected at its inner end with a hand lever 12 projecting forwardly over the hopper, as will be understood, so that 60 by shifting the hand lever in an obvious manner the clutch-controlling lever will be rocked to close or open the clutch. A retractile spring 13 is also attached to the upper extremity of the clutch-controlling 65 lever and to a bracket or other fixed member upon the hopper, as indicated at 14. Pivoted at the lower end of the clutch-controlling lever is a latch 15 which extends inwardly therefrom and has its inner end 70 beveled, as shown at 16, and is provided in its lower edge adjacent its inner end with a notch 17. Bracket plates 30 are secured to the opposite sides of the lever and project laterally therefrom, the latch being pivoted 75 to and between the projecting portions of said plates, as shown in Figs. 3 and 4, and it will be noted, upon reference to Fig. 4, that the pivoted end of the latch is beveled in its upper portion, as at 31, whereby the 80 upward movement of the latch is accommodated while the lower portion, 32, of the end edge is at a right angle to the bottom edge and may abut the edge of the lever whereby the latch will be prevented from dropping 85 too far to operate. A keeper and guide 18 is also secured to the lever and consists of a plate offset, as shown in Fig. 4, to engage over the vertical flange or web of a lateral arm 19 secured to and extending outwardly from the frame of the machine, and upon this arm or bracket is secured a loop or eye 20 which registers with the notch 17 90 in the latch when the latch is in active position. Through this eye or loop plays the 95 rear end of a locking rod 21 which is slidably supported in the eye and extends forwardly to be connected to an angle lever 22 mounted upon the frame at the front end thereof, the rod being jointed at an intermediate point of its length, as shown at 23, to accommodate the relative angular relation of the parts during operation. A sleeve 24 is carried by the bracket or arm 19 100 in alinement with the loop or eye 20 so as to aid in supporting the rod 21 and also furnish an abutment for a spring 25 which is coiled around the rod between said sleeve

In the drawings:

Figure 1 is a side elevation of a portion of 25 a corn-husking machine having the invention applied thereto; Fig. 2 is an enlarged transverse section of the machine frame showing the clutch-controlling lever and the parts immediately adjacent the same in side elevation;

Fig. 3 is an enlarged horizontal section on the line 3—3 of Fig. 1;

Fig. 4 is a detail perspective view of the latch and the parts cooperating therewith;

Fig. 5 is an elevation of a portion of the hopper;

Fig. 6 is a detail perspective view of a portion of the clutch lever and the means for actuating the same;

Fig. 7 is a detail showing another form of latch.

The husking machine 1 may be of any desired form and includes a shaft 2 which drives some of the working elements and is equipped with a loose pulley 3 with which cooperates a clutch cone 4 whereby the pulley may be locked to the shaft. A band 5 is trained around the pulley and transmits motion thereto from a main driving shaft 6. Carrying the cone clutch member 4 and having a pin and slot connection therewith, as shown at 7, is a controlling lever 8 which is fulcrumed upon a bracket 9 above the pulley and extends above and below the same,

and a collar or other abutment 26 secured upon the rod. The front end of the rod 21 is pivoted to the lower depending arm of the angle lever 22 and the other arm of said 5 lever projects forwardly and has the lower end of a link 27 pivoted thereto. Pivoted mounted upon the frame of the machine above the angle lever 22 is a platform 28 upon which the operator stands when the 10 machine is in operation and the upper end of the link 27 is pivoted to the platform, as shown, so that when the platform is depressed the rod 21 will be pushed rearwardly to engage in the notch 17 of the latch and 15 thereby hold the clutch in closed position.

Assuming the machine to be in operation, the platform 28 will be in the lowered position shown by dotted lines in Fig. 1, and to prevent the platform dropping below said 20 position a chain or other restraining device, indicated at 29, may be provided and attached at one end to the platform and at the other end to the machine frame. When the platform is lowered, the angle lever 22 will 25 be rocked so that the rod 21 is pushed rearwardly and will be in position to engage the notch 17. When the operator initially takes his position upon the platform, the clutch will be open and the lower end of 30 the controlling lever 8 will be at the outer limit of its movement with the latch 15 disposed outwardly with respect to the rod 21. After assuming his position upon the platform, the operator shifts the hand lever 12 35 so that the controlling lever 8 will be rocked to throw the clutch in and this movement of the controlling lever will, of course, carry the latch 15 inwardly, the inner beveled end of the same riding over the rod 21 and the 40 notch 17 dropping into engagement with the rod. Should the operator leave the platform, the spring 25 will immediately expand so as to withdraw the rod 21 from the notch 17 and the spring 13 will then at 45 once contract so as to rock the clutch-controlling lever 8 and open the clutch, the machinery being thus automatically stopped whenever the operator may leave the platform. When the operator resumes his position 50 upon the platform, the clutch will remain open inasmuch as the spring 13 will be contracted and the clutch will not be closed until the operator shifts the hand lever 12 to throw the clutch in.

55 In Fig. 7 is shown a simpler form of latch which is very efficient but costs less than the first-described form. The clutch-controlling lever 33 is mounted and operates in the same manner as the lever 8 but the 60 latch 34 is slidably mounted on the lower end of the lever to move vertically thereon, and its lower end is beveled, as at 35, so that, in the clutch-closing movement of the lever, it will ride over the trip or locking 65 rod 36 and drop into position at the side of

the rod to be held against return movement. A stop collar 37 is secured on the lever within an opening 38 in the latch, and a spring 39 is coiled around the lever between said collar and the lower wall of 70 the opening to yieldably hold the latch in its lowest position, the descent of the latch being limited by contact of the upper wall of the opening with the stop collar.

From the foregoing description, taken in 75 connection with the accompanying drawings, it will be seen that we have provided an exceedingly simple, compact and inexpensive mechanism which may be readily applied to any machine and by which the 80 working elements will be automatically and instantly stopped whenever the operator leaves his position, and they will remain inoperative until after the operator has resumed his position and manually throws in 85 the clutch.

Having thus described the invention, we claim:

1. In combination with a clutch-controlling lever, a latch carried by the lever, a 90 locking rod adapted to engage the latch and hold the clutch closed, said rod being normally free of the latch, means for rocking the lever to close the clutch and means whereby upon withdrawal of the locking 95 rod the clutch-controlling lever will be actuated to open the clutch.

2. The combination with a clutch-controlling lever, and means for manually actuating the lever to close the clutch, of a latch carried by the lever, a locking rod for engaging the latch to hold the clutch closed, means whereby the locking rod will be projected to engage the latch when an operator is in position and will be withdrawn when the operator leaves his position, and a retractile spring attached to and operating upon the clutch-controlling lever, in opposition to the first-mentioned means to open the clutch when the latch is released. 110

3. The combination of a normally inactive controlling element, a locking rod connected with said element to move into active position therewith, means yieldably holding the rod and said element in inactive 115 position, a clutch-controlling lever, a latch carried by the lever to be engaged by said rod whereby the clutch may be held closed, means for manually shifting the lever to clutch-closing position, and a spring acting 120 on the lever in opposition to said manual means for opening the clutch when the latch is released from the locking rod.

4. The combination with a machine frame, and a movable platform mounted thereon, of a locking rod operatively connected with the platform and supported on the machine frame, means for yieldably holding the rod and the platform in inoperative 125 position, a clutch-controlling lever, 130

a latch carried by said lever and having its free end beveled to ride over the locking rod and provided with a notch to engage said rod when the rod has been shifted to active position by movement of the platform, means for manually shifting the lever to clutch-closing position, and means for

automatically shifting the lever into clutch-opening position upon withdrawal of the locking rod from the latch. 10

In testimony whereof we affix our signatures.
